UNITED STATES PATENT OFFICE

2,488,132

DEFLECTION SYSTEM FOR CATHODE-RAY TUBES

Herndon Wheeler Leighton, Hackensack, N. J., assignor to Allen B. du Mont Laboratories, Inc., Passaic, N. J., a corporation of Delaware

Application October 30, 1946, Serial No. 706,727

6 Claims. (Cl. 250—159)

1

This invention relates to a cathode-ray tube and more particularly to the deflection system thereof.

In accordance with this invention provision is made for connecting coaxial cables to deflection plates of cathode-ray tubes and these plates are so shielded that very high frequencies can be applied to them with a minimum of interference from outside sources. Also, the inductance of the circuit is kept low and capacitances between electrodes of the tube are minimized.

In carrying out the invention, provision is made so that the outer conductors of coaxial cables can be attached to threaded connectors that are made up of several pieces that pass through the wall of the neck of the tube. The length of the conductors inside of the neck is very short due to the fact that the conductors enter the neck radially.

A shield is provided inside of the neck of the tube around the deflection plates to protect them from external interference and another shield is provided to separate the horizontal from the vertical deflection plates to prevent the two fields from interacting or influencing each other.

The invention may be understood from the description in connection with the accompanying drawings, in which:

Fig. 1 is a longitudinal section through the neck of the tube partly broken away.

Fig. 2 is a perspective view of the rings that hold the deflection plates and their connectors in position.

Fig. 3 is a perspective view of one of the outer coaxial connector bushings.

Fig. 4 is a plan view of the deflection plate assembly and,

Fig. 5 is a side view of the deflection plate assembly partly along the section 5—5 of Fig. 4.

Fig. 6 is a plan view of a modified form of the deflection plate assembly shown as a section across the neck of the tube to show how the assembly is mounted.

Fig. 7 is a longitudinal section through the neck of the tube, as shown in Fig. 6, partly broken away.

In the drawings, reference character 1 indicates a portion of the neck of a cathode-ray tube through the walls of which four coaxial connectors extend. A portion 2 of each coaxial assembly is anchored in the neck 1 and makes contact with the outer coaxial connector bushing 3 that is held in place by the seals consisting of a corn plaster shaped piece of ceramic 4 and cement 5.

The bushing 3 which is externally threaded

2

to receive the outer lead of the coaxial cable has struck-out tabs 3a to form a tight fit in the tubular connector 2. This bushing is flanged at 3' to hold its position against the neck of the tube 1. Each one of these bushings is inserted into a connector 2 and is cemented to the glass neck 1 by seals 4 and 5.

The inner end of portion 2 fits into a connector tube 6 and is welded to it as indicated at 7. The connector 6 is mechanically attached so as to be vacuum tight to an inner connector 8—10 by the insulating material 9. The slit portion 10 is provided to receive the inner conductor of a coaxial cable. This slit portion is supported by the ring of insulating material 9 and is spot welded at 11 to the deflection plate lead 12 which supports the deflection plate 13.

Metal rings 14 and 15 (Figs. 1 and 2) are provided with grooves 14' and 15' and are clamped together by bolts 16 and nuts 16' to hold these rings on the connectors 6. These connectors 6 are cemented to the rings 14 and 15 as indicated at 6'.

Electrostatic shields 17 and 18 that have flanges 17' and 18' are bolted onto the deflection plate assembly by nuts 16'' on the bolts 16. A disc shaped shield 19 (Fig. 5) having a central hole 19' for the electron beam is clamped between the discs 14 and 15.

30 In the final assembly of the tube the deflection plate sub-assembly as shown in Figs. 4 and 5 may be attached to the electron gun structure, not shown. The stem carrying the electron gun structure and the deflection plate assembly is then inserted in the neck of the tube and adjusted until the deflection plates are at the proper distance from the screen of the tube. The stem is then sealed in place. Each of the flanged portions 2 of the deflection plate assembly will then be in close proximity to the inside wall of the neck 1 of the tube. The glass of the neck 1 is then heated and pushed down around the flanged portions 2 so as to complete a vacuum tight seal at this point. Holes are then melted through the glass over these flanged portions 2 permitting the connectors 3 to be inserted so as to give good electrical contact between them, with the flange 3' resting on the seal between the neck and the curved portion of 2. The corn plaster shaped seals 4 are then put in place over flange 3' and affixed with cement 5 so as to hold flange 3' firmly in place with respect to the curved portion 2 to complete the operation.

55 Figs. 6 and 7 show a modification of the deflec-

tion plate assembly and the way it is mounted in the neck of the tube.

As shown in these figs. the part 20 corresponding to part 2 of the other figs. does not have the curved flange shown in Figs. 1, 4 and 5 at the point where it fits into the glass. It goes straight through and a threaded and flanged piece 21 fits over it and receives the outer coaxial connector on its threads.

In this modification, a conductor 22 connects the inner conductor of the coaxial line with the connector 10 attached to connector 11 that supports the deflection plate 13. It is supported along the axis of the outer connector 20 by a bead 23 of glass which provides a vacuum tight seal.

The deflection plate lead assembly shown in Figs. 6 and 7 is held in position by threaded metal pieces 24 and 25 which fit each other and the sleeve 20 and are so arranged as to make good electrical contact between the parts 20 and 26.

The transverse shield 27 of the deflection plate 13 is constructed with a recess 28 to receive the deflection plate connectors.

In the final assembly according to Figs. 6 and 7 the deflection plate assembly without the bushing 21 is inserted into the tube neck. After locating the deflection plate assembly the tube neck is heated and sealed about the four connectors 20 to the tube body. The bushings 21 are then slipped over the protruding portions of the sleeves 20 and are sealed in place as before with the cornplaster shaped seals 4 and the cement 5.

What is claimed is:

1. In a cathode-ray tube having deflection plates, a metal shield for said plates, means to connect the inner conductor of a coaxial cable to each of said plates through said shield and means to attach the outer conductor of said cable to said shield.

2. The device of claim 1 in which the last mentioned means of attachment of the outer conductor of said cable to the shield comprises a tubular member with one end set in the shield and the other set in the glass neck of the tube and protruding from it with this protruding portion adapted to receive the outer conductor of the coaxial cable.

3. The device of claim 1 in which the last mentioned means of attachment of the outer conductor of said cable to the shield comprises a tubular

member with one end set in the shield and the other having a recurved flange and set in the glass neck of the tube and a bushing having its outer portion adapted to receive the outer conductor of a coaxial cable inserted into the flanged portion of the tubular member.

4. In a cathode-ray tube, a plurality of coaxial lines passing through the wall of the neck of said tube and each having its outer conductor hermetically sealed in said wall and a shield for deflection plates in said tube to which the outer conductor of each of said cables is attached.

5. In a cathode ray tube having two pairs of deflection plates, a cylindrically shaped metal shield for said plates, means to connect the inner conductor of a coaxial cable to each of said plates through said shield and means to attach the outer conductor of said cable to said shield, and comprising two pairs of semi-cylindrical metallic members attached to said shield and extending inwardly therefrom forming complementary shielding channels for conductors leading to said plates.

6. In a cathode ray tube having two pairs of deflection plates, a cylindrically shaped metal shield for said plates, means to connect the inner conductor of a coaxial cable to each of said plates through said shield and means to attach the outer conductor of said cable to said shield, and a metal disc provided with a central aperture aligned with the axis of the tube positioned between pairs of said deflection plates and electrically connected to said cylindrically shaped metal shield.

HERNDON WHEELER LEIGHTON.
